DESIGN FOR AN ADVERTISING SIGN

George Jaehnigen and Robert E. L. Lamb,
Atlanta, Ga.

Application December 16, 1933, Serial No. 50,098

Term of patent 7 years

To all whom it may concern:

Be it known that we, GEORGE JAEHNIGEN and ROBERT E. L. LAMB, citizens of the United States, residing at Atlanta, in the county of Fulton and State of Georgia, have invented a new, original, and ornamental Design for Advertising Signs, of which the following is a specification, reference being had to the accompanying drawing, forming part thereof.

In the drawing:

Figure 1 is a view in perspective of an advertising sign, showing our invention,

Figure 2 is an end view, and

Figure 3 is an opposite end view.

We claim:

The ornamental design for an advertising sign, as shown.

GEORGE JAEHNIGEN,
ROBERT E. L. LAMB.
